(57) **CLAIM**

The ornamental design for a crafting apparatus, as shown and described.

DESCRIPTION

FIG. 1 is a front, right, top isometric view of the crafting apparatus in a first position (showing presently unclaimed workpiece support arms in a stowed position);

FIG. 2 is a front elevation view of the crafting apparatus in the first position;

FIG. 3 is a rear elevation view of the crafting apparatus in the first position;

FIG. 4 is a left side elevation view of the crafting apparatus in the first position;

FIG. 5 is a right side elevation view of the crafting apparatus in the first position;

FIG. 6 is a top plan view of the crafting apparatus in the first position;

FIG. 7 is a bottom plan view of the crafting apparatus in the first position;

FIG. 8 is a front, right, top isometric view of the crafting apparatus in a second position (showing presently unclaimed workpiece support arms in a deployed position);

FIG. 9 is a front elevation view of the crafting apparatus in the second position;

FIG. 10 is a rear elevation view of the crafting apparatus in the second position;

FIG. 11 is a left side elevation view of the crafting apparatus in the second position;

FIG. 12 is a right side elevation view of the crafting apparatus in the second position;

FIG. 13 is a top plan view of the crafting apparatus in the second position; and,

FIG. 14 is a bottom plan view of the crafting apparatus in the second position.

The broken lines in the figures show portions of the crafting apparatus that form no part of the claimed design.

1 Claim, 14 Drawing Sheets
